Specification of Letters Patent.

Patented Jan. 9, 1917.

Application filed April 15, 1914. Serial No. 832,073.

To all whom it may concern:

Be it known that I, CHARLES H. HOWARD, a citizen of the United States, residing at Saugus, county of Essex, and State of Massachusetts, have invented an Improvement in Paper-Reinforcing Machines, of which the following description, in connection with the accompanying drawings, is a specification, like letters on the drawings representing like parts.

The invention to be hereinafter described relates to paper-reinforcing machines, and more particularly to that type of such machines wherein the paper fabric is strengthened by means of crossing threads of textile or other material.

Attempts have heretofore been made to provide a machine of this general character, wherein rotatable means have been employed for carrying the spools or other source of supply and other rotative means for drawing the threads from the first rotatable means and laying them transversely of the fabric. In such case, however, much difficulty has been experienced in properly maintaining the transverse threads in position until they become secured to the paper fabric, and the heavy weight necessarily carried by the rotatable means has introduced objections to its economic operation. Other attempts have been made to overcome the troubles incident to the employment of such rotary machines by providing devices to grasp and hold the transverse threads and delay the cutting thereof until such threads had been delivered to and between the rolls for impressing them upon the fabric. Still further attempts along this general line have been made by drawing in the transverse threads singly by reciprocating means, but this has been economically objectionable and slow in operation, and has also required that the transverse threads be delivered directly between the fabrics to which they were to be united, so that such threads could not get out of position before being secured therebetween. The objections to these previous attempts to provide a paper-reinforcing machine of practical efficiency have been incident to the character of the construction and principles of operation.

The aims and purposes of the present in-

vention are to provide a machine of this general type, that is, one for reinforcing paper or other fabrics, which shall be simple in construction, efficient and economical in operation, and wherein the transverse threads may be delivered to the paper or other web of material while still maintaining their proper transverse positions,—all of which will best be made clear from the following description and accompanying drawings of one form of means for carrying the invention into practical effect, it being understood that the invention is not restricted to the details of such means, but that these may be varied within the true scope of the actual invention, which is definitely pointed out by the claims.

In carrying the general purposes of the invention into effect, the web of material is fed longitudinally and gripping means is provided for carrying a series of transverse threads from a source of supply transversely of the machine and then relatively moving the series of transverse threads and web of material to be reinforced toward each other for delivery of the series of threads to the surface of the web. It is desirable for the best results and economic production, that the web to be reinforced be fed continuously, and means are provided by the present invention to maintain positive control of the transverse threads after they have been severed from the source of supply until they are laid in their final position on the surface of the web at which time they are freed and pass along with the web itself. This feature of the invention is of importance in that it insures correct position of the transverse threads at all times, and in the finished product uniformity of transverse direction of the threads results. In the present instance of the invention, a transverse thread carrier is provided at each side of the machine, which take the threads from the grippers and move in rectilinear paths while still holding the ends of the transverse threads until they are deposited on the surface of the web and then release the ends of the threads. It may be expedient in some aspects of the invention to dispense with the carriers, but in the present instance the carriers at each side of the machine are prefer-

ably employed because the carriers may be given appropriate movement with respect to the traveling web without complication of mechanical movements in connection with 5 the grippers themselves.

The gripping means may, of course, be varied in construction within the scope of the invention as defined by the claims, but in the present instance there is provided a 10 series of grippers at each side of the machine and they are moved toward each other to draw the transverse threads from the supply and deliver the ends of the threads to the series of grippers at the opposite side of 15 the machine and then they are separated so that the grippers at the non-supply side complete the transverse movement of the series of threads, while those at the supply side move back for another hold. In this aspect 20 of the invention the transverse threads are severed in front of the supply grippers after each transverse movement.

The web, such as paper which is to be reinforced, may be supplied either from suitable rolls or, if desired, the reinforcing machine may be associated with a paper-making machine and receive its supply directly therefrom, as the paper is made.

The rectilinearly-moving carriers which 30 take the transverse threads from the grippers may be variously devised to carry into effect their intended purposes, but in the present instance a convenient and efficient means consists in a series of links, something like a chain, having clips or holders which can take the threads from the grippers. To effect this action, the grippers and carriers are relatively moved toward each other after the threads have been drawn 40 from the supply by the grippers, and in the present instance it is found expedient to move the grippers toward the carriers, but obviously a relative movement of the two devices is the only essential in this respect.

45 In the drawings:—Figure 1 is a side elevation of a machine embodying one form of the present invention, the lower portion of the framework being omitted; Fig. 2 is an end view of the parts shown by Fig. 1, looking from the right, Fig. 1; Fig. 3 is an enlarged detail, parts being shown in section, showing more particularly the means for drawing in and delivering the transverse threads; Fig. 4 is a view in general side elevation, looking in the direction of the arrow *a*, Fig. 3, some of the parts being shown in section and others broken away; Fig. 5 is a section on the line 5—5, Fig. 4; Fig. 6 is a detail showing the gripping jaw construction at the supply side of the machine; Fig. 7 is a detached detail with some of the parts in section, showing the cutter-carrying frame; Fig. 8 is a section on the line 8—8, Fig. 1, the parts being enlarged for the purposes of clearness; Fig. 9 is a section on the

line 9—9, Fig. 4; Fig. 10 is a section on the line 10—10, Fig. 3; Fig. 11 is an enlarged side elevation showing more particularly the transverse thread-carrying chain, the clips for holding the transverse threads and one 70 form of means for freeing the threads from the clips, some of the parts being shown in section and others broken away; Fig. 12 is a section on the line 12—12 of Fig. 11; and Fig. 13 is a view of a fabric reinforced by 75 longitudinal and transverse threads.

The frame 1 of the machine may be of any desired or approved character for properly supporting the operating parts, and, as indicated in Figs. 1 and 2, has mounted thereon in suitable bearings, the driving shaft 2 provided with fast and loose pulleys 3 and 4, Fig. 2, whereby the operating parts may be driven by belting from any suitable source 85 of power.

Secured to the driving shaft 2 is a gear 5, Fig. 1, operatively engaged with an idle gear 6, which is itself in operative engagement with a gear 7 mounted on a shaft 8 supported by suitable bearings on the machine frame. Above the shaft 8 is the shaft 9 carried by suitable blocks 10 for the desired adjustment, and secured to said shaft is a gear 11 for transmitting power through the gears 12, 13 and 14 to a shaft 15 carrying a sprocket-wheel 16. Mounted on the upwardly-extending frame member 17 at the right, Fig. 1, is a cam shaft 18 provided with a suitable sprocket-wheel 19, Fig. 2, whereby the cam shaft 18 may be driven from the shaft 15 through the sprocket-chain 20, Fig. 2, the construction being such that upon rotation of the driving shaft 2 and by reason of the operative connections described in the present instance of the invention, the cam shaft 105 18 may be properly driven for purposes to be hereinafter described.

The present invention contemplates as a preferred form thereof, that both longitudinal and transverse threads may be laid on 110 the web in crossed relation to reinforce it. It further contemplates, in some instances, that the reinforcing threads be placed between two superposed plies or webs of paper or other fabric. In this latter case, 115 which will be described as a preferred form of the invention, the shaft 9 has mounted thereon, as indicated by the broken lines in Fig. 1, the roller 21 about which is passed the paper 22 which is drawn from a suitable supply not shown. Also mounted upon the framework of the machine is a shaft 23 carrying a cylinder 24 about which passes a web of paper 25 drawn from a suitable supply 26, as indicated by Fig. 1 and constituting 125 one form of guiding device. It is preferred that the surface of the paper web be supplied with an adhesive, either prior to its introduction in the machine or as it is introduced thereto, and as one form of the in- 130

vention in this respect, the web of paper 25 as it is drawn from the roll or supply 26, is made to pass over an adhesive-applying roller 27, Fig. 1, so that the surface of the 5 web of paper 25 which is to be next adjacent to the web of paper 22, as will presently appear, is supplied with an adhesive. Obviously the web 25 might be supplied with gum and dried before being brought to the 10 machine, in which case the roller 27 may simply dip into a moistening tank to apply moisture to the already gummed surface or the paper may be supplied directly from a 15 paper making machine. From the construction described and as illustrated in Fig. 1, it will be noted that the roll 24 about which the web 25 passes, is in advance of the roll 21 about which the web 22 passes, which is a construction preferably employed and utilized in the present instance for applying 20 to the gummed surface of the web 25 a portion of the longitudinal and all of the transverse threads, as will presently appear, before the remaining longitudinal threads are 25 introduced.

The longitudinal threads might, of course, all be supplied from one common source, and laid longitudinally of the paper webs side-by-side in separated relation and on 30 one side of the transverse threads, that is, all on top or all beneath such transverse threads, but in the preferred embodiment 35 of the invention it is desired that the longitudinal threads shall be alternately arranged over and under the transverse threads, as indicated in Fig. 13. To carry this feature of the invention into effect, part of the longitudinal threads 28, as indicated by dotted lines in Fig. 1, are introduced 40 from a suitable source of supply directly upon the gummed surface of the paper web 25 in separated relation and similarly, the longitudinal threads 29, Fig. 1, are introduced above the roll 21, it being 45 understood that the group of threads 28 and 29 are alternately arranged side-by-side, that is, first a thread 28, and then a thread 29, then a thread 28, and then a thread 29, will appear transversely of the 50 finished fabric, as indicated in Fig. 13, so that the transverse threads being supplied to the gummed surface of the paper web 25, will appear to be arranged over and under adjacent longitudinal threads, as will more 55 fully appear. The longitudinal and transverse threads being arranged preferably as described, it is desirable that the two fabrics 22 and 25 be then forced into intimate surface contact. As one means to this 60 end there is mounted upon the shaft 8, a roller 30, Fig. 1, which is adapted to cooperate with the roller 21 on the shaft 9, so that as the transverse and longitudinal threads, arranged as described, pass with 65 the paper web 25 between the rollers 21 and

30, said rollers act to press the two surfaces of the paper webs into intimate contact, thus permanently securing the threads and paper web in their associated relations.

In order that different thicknesses of 70 paper may properly be employed, one of the shafts 8 or 9, preferably 9, is provided with adjusting devices 31, Fig. 1, whereby the block 10 carrying the said shaft 9 may be raised or lowered, as conditions require, 75 the finished paper passing as indicated by the arrow *b* in Fig. 1, and taken up by suitable means not necessary to describe.

As hereinbefore noted, the present invention 80 contemplates that the transverse reinforcing threads or filaments shall be drawn from a source of supply in plural numbers and carried or drawn simultaneously in substantially parallel relation transversely of the machine or transversely relative to 85 the material to be reinforced, and that they then be released so that they may move along with the material to be reinforced as they are applied thereto. It will be convenient at this time to describe one form 90 of means within the contemplation of the invention for taking a plurality of independent threads from a source of supply, preferably located at one side of the machine, and simultaneously placing them in 95 parallel relation transversely relative to the material to be reinforced.

Mounted in suitable bearings 32, Figs. 1 and 2, surmounting the frame of the machine, are the two shafts 33 from which project the arms 34 carrying the side shafts 35, Figs. 3 and 4, from which depend the transverse thread-drawing-in-arms. In the preferred form of the invention, as illustrated in the drawings, the transverse 100 threads are carried partially across the transverse width of the carrier chain to be described by one gripper means, and then grasped by another gripper means and drawn the remainder of the distance, and 105 while this is the preferred form, it may not always be necessary to use both gripper means. Since these two means, except as to the particular form of jaws, and their operating means, are alike, a description of 110 one will be sufficient, reference being made particularly to Figs. 1, 2, 3 and 4.

Mounted upon the shaft 35 is a sleeve 36 having an upwardly-extending web 37, Figs. 4 and 5, secured to said shaft 35 to rock 120 therewith by suitable means such as the set screws 38. The sleeve 36 is slotted at intervals at 39, as indicated in Fig. 4, and mounted upon the shaft 35 and within the slots 39 are the transverse oscillatory thread 125 arms 40. The slots 39 are of sufficient extent circumferentially of the shaft 35 to permit the oscillatory arms 40 to be swung relative to the sleeve 36 when they are freed to such swinging action. Extending from 130

the shaft 35 is the rocker arm 41 carrying a suitable roll 42 to engage a cam path 43 of a cam 44 secured to the cam shaft 18, Figs. 1, 2 and 4, the construction being such that upon rotation of the cam 43, the shaft 35 and perforce the sleeve 36, will be given an oscillatory movement, and should the oscillatory thread arms be connected to the sleeve at such time, they, likewise, will be given an oscillatory movement. In order to secure such oscillatory movement of the thread arms 40, the latter are provided with upwardly-extending portions 45, adapted to be engaged by a catch 46, Fig. 5, pivoted at 47 to suitable lugs projecting from the web 37, and normally under the influence of a spring 48 tending to hold the catches in engagement with the upper ends of the thread arms. The lower portion of the catches 36 may be conveniently provided with a tail or hand-piece 49, Fig. 5, whereby, when desired, any one of the thread arms, when a plural number is employed, can be operatively disconnected from the sleeve 36, to enable repairs or alterations to be made therein, as dictated by the conditions of use.

From the construction thus far described, it will be noted that the oscillatory thread arms 40 are loosely hung to the shaft 35 and are operatively connected therewith through the sleeve 36 and web 37 and the catches 46, said catches being adapted to readily be disengaged from the thread arms to free them when desired. As indicated in the drawings, the transverse oscillatory thread arms are eight in number, whereby, as will presently appear, a series of threads, either eight or sixteen, or even more, may be drawn from the source of supply and laid transversely of the thread carrier, to be described. Obviously the number of thread arms may be varied within the true scope of the actual invention, but they should be such in number for the best practical results, that they will complete a transverse thread drawing movement during the time necessary for threads previously laid upon the carrier to be moved from under the path of the thread arms in a direction of approach relative to the material to be reinforced, as will be readily understood, whereby the continuous and rapid operation of the machine is better effected.

Supported in suitable position, preferably at the side of the machine, are a series of spools from which the transverse threads are to be drawn. This source of supply is best shown in Fig. 2, wherein the spools 50 are carried upon suitable brackets 51, projecting from the side of the machine frame, said brackets also serving as a support for a suitable arm 52, carrying suitable tension means 53 to act upon the thread. Since the threads are delivered at the side of the machine, and since there are two sets of trans-

verse oscillatory arms 40, the present invention contemplates providing the thread arms adjacent the supply side of the machine with a form of jaw for grasping the thread ends and carrying these threads 70 toward the median line of the machine where they may be grasped by the jaws of the oscillatory arms 40 at the opposite side of the machine and be by them drawn through the jaws of the arms at the supply 75 side of the machine as the respective arms return to the outer position, the effect being that during such movement the threads will be drawn through the jaws of the arms at the supply side of the machine by the arms 80 at the opposite side of the machine, and when the threads are cut, as will hereinafter appear, the jaws at the supply side of the machine will still maintain their hold upon the threads with an end of each thread projecting sufficiently far beyond the jaws to be engaged by the jaws of the opposite arms. From what has been said, it will be apparent that the jaws on the arms at the supply side of the machine are somewhat different from those on the opposite side of the machine, and such jaws will now be described, reference being made particularly to Figs. 2, 3, and 6.

Each of the arms 40 at the supply side of the machine has at its lower end a fixed jaw 54, which may comprise a continuous bar-like structure, as indicated in Fig. 6. Pivotally mounted at 55 are the two upper jaws 56, each adapted at its lower end to grasp the end of a thread 57 between it and the lower portion, such grasping action being under the influence of a spring 58, which is preferably split, as indicated in Fig. 6, to permit one arm of each of the legs to act 105 upon a pin 59, extending from the side of the upper jaws 56, Fig. 6, the construction being such that while the upper jaws 56 under the action of the spring 58, will grasp the threads 57, preferably plural in number, upon the lower jaw as the arms 40 move to the right, Figs. 2 and 3, and thereby cause the threads to be drawn from the source of supply, yet, such threads may be drawn to the right between the jaws 54 and 56 without material obstruction.

The thread engaging jaws on the oscillatory arms at the side of the machine remote from the source of supply comprise a fixed lower jaw and a spring-actuated jaw with means for separating the jaws to release the free end when the thread has been placed in its desired position. As one convenient form of means to this end, these jaws comprise a fixed jaw 60 and a sleeve 61 carrying a jaw 62, Figs. 3 and 5, said sleeve being normally under the influence of a spring 63, whereby the jaws 60 and 62 are normally held in closed position. The sleeve 61 is connected to a jaw-operating member 64 120

extending upward along the side of the oscillatory arms 40, and having at its upper portion a projection 65, preferably secured to the jaw-operating member 64 by means of 5 pins 66, Fig. 5. In order to separate the jaws at the desired time, the projection 65 overlies a jaw-operating device, a good practical form of which is indicated in Figs. 1, 3 and 4.

10 Mounted to rock upon a shaft 67, Fig. 3, are the jaw opening arms 68, the ends of which underlie rolls 69 mounted on the sleeves 70 free to slide relative to the arms 41 and 71, Fig. 4. This sliding relation of 15 the sleeves and arms 41 and 71 extending from the shaft 35, may be formed in any suitable manner, and a convenient construction being indicated by Fig. 9, wherein the arm 41 and likewise the arm 71, may have a 20 guiding member 70 secured thereto for engagement with the sleeves 70. Since there are a plural number of oscillatory arms 40, each carrying the described form of jaw construction, at the side of the machine remote from the source of supply, the sleeves 25 70 are connected by a lifter 72, Figs. 1, 4, and 5, which underlies the series of projections 65 connected to the jaw-operating rods 64. Mounted at 73, Fig. 1, is a lifter arm 30 74, having a toe 75 adapted to engage a path cam 76 on the cam shaft 18, Fig. 2, the end of the lifter arm 74 being extended beneath the opening arms 68 as shown in Figs. 1 and 3, the construction being such that upon 35 rotation of the cam shaft and at suitable times, the lifter arm 74 will raise the arms 68 and the lifter 72, thereby opening the jaws for free and ready release of the threads.

40 When the transverse threads have thus been drawn from the source of supply and carried transversely as indicated, and before the jaws release the transverse threads, it is desirable that the jaws be lowered in order to place the transverse threads in engagement with the material or web to be reinforced or the transverse thread carrier, to be described, for delivery to the gummed surface of one of the fabrics. To 45 this end the shafts 33, Figs. 2 and 3, have secured thereto the arms 77 provided with rolls 78 which engage suitable cam paths 79, Fig. 2, the construction being such that prior to the release of the threads by the 50 jaws in the manner hereinbefore noted, the oscillatory arms 40 are lowered to carry the thread from the full to the dotted line position, Fig. 3, in which latter position the thread is brought into engaging position 55 for the thread carrier, as will presently appear. The means for thus carrying the series of threads transversely of the machine constitute grippers for seizing and releasing the threads, and while the oscillatory arms have been described as the form of the

invention in the present instance, the invention is not limited in this respect, and the term "gripper" or "gripper means" will be hereinafter employed as a broad term including not only the oscillatory arms and 70 their associated features, but any devices having jaw parts for seizing the threads and carrying them transversely whether they oscillate or have other character of movements transversely of the machine.

75 After the thread has been drawn into its transverse position as described, and the grippers have been lowered as hereinbefore noted, and prior to or at the time the grippers remote from the source of supply release the threads, the latter should be cut from the source of supply in front of the grippers at the supply side of the machine. As one means for thus cutting the threads, there are pivotally mounted on the machine 80 frame at 80, knife operating arms 81, Figs. 2, 7 and 8, normally under the influence of a spring 82 tending to lift said knife operating arms. The knife operating arms 81 may preferably be formed as part of a frame as 85 indicated in Fig. 7, but of course this detail is susceptible of variations. Associated with the knife operating arms 81 is a controller arm 83 having a roll 84 normally resting upon the surface of a cam 85, Fig. 95 2, connected to the shaft 86, whereby when the low part of the cam arrives opposite the roll 84, the knife operating arms 81 will rise in response to the spring 82. If desired, the action of the knife operating arms 100 may be more quickly controlled by providing a finger 87 on the controller 83 adapted to engage at times with the flanged abutment 88 made as part of the cam 85, so that while the roll 84 may normally maintain the 105 knife operating arms 81 depressed, this action will pass into the control of the finger 87 at the time when the projection 88 engages said finger, so that as the projection 88 passes, the finger will suddenly rise into 110 the depression, thus suddenly raising the knife operating arms 81.

The arms 81 project toward the side of the machine as indicated in Figs. 2, 7 and 8, and underlie the studs 89 which rise 115 through the sleeves 90 extending from a part 94 of the machine frame, and have secured at their upper portions the knife carrying plate 91. The knives 92 may be of any appropriate form, but, as indicated in 120 Figs. 1 and 8, they are preferably formed wedge-shape at their cutting edges and detachably secured to the plate 91 by means such as the screws 93 or otherwise, the construction being such that when the knife 125 operating arms 81 rise, they will act upon the studs 89 and raise the knives 92 into the position to cut the threads in front of the jaws of the oscillating arms at the supply side of the machine. The knives 92 should 130

be of sufficient extent, as indicated in Fig. 1, to cut all of the threads that have been laid by the oscillating arms at one cycle of their operations.

5 It will be obvious, of course, that the character of the grippers for drawing in the transverse threads, the particular means for giving transverse movement to these grippers whereby they approach and recede from 10 each other in drawing in the transverse threads, and the particular means for throwing the cutters into operative position, may all be changed within the true scope of the 15 actual invention; but the mechanism hereinbefore described has been found to be convenient and well adapted as a mechanical organization for the intended purpose.

As hereinbefore described, the present invention contemplates the simultaneous drawing out of a plural number of transverse threads from a source of supply, and delivering these threads to the material or web to be reinforced or to a carrier to be by it in turn delivered directly to the gummed 25 or adhesive surface of a paper or other fabric. The transverse threads are light, fluffy, and easily disturbed when once released from the jaws of the grippers, and therefore the present invention proposes to positively engage the series of threads just as such threads are released from the control of said gripper means, and then to carry such threads under positive control into direct contact with the gummed or adhesive 30 surface, where they will maintain their desired positions. As one form of means to this end, there is arranged at each side of the machine, a transverse thread carrier which moves in a straight path longitudinally of and substantially parallel to the median line of the machine frame in a direction of approach relative to the material to be reinforced, each of said carriers having appropriate means for taking the transverse 35 threads and delivering them to the adhesive or gummed surface of the fabric. Such carriers, there being one at each side of the machine, are substantially alike, and therefore the description of one will serve 40 for both, reference being particularly had to Figs. 1 and 11.

Mounted in the machine frame, Fig. 1, is a shaft 95 provided with sprocket-wheels 96. The driving shaft 2 at the opposite end of 45 the machine is likewise provided with a sprocket-wheel 97, Figs. 1 and 11. Between these sprocket-wheels, there being one at each end of the respective shafts 2 and 95, are extended the transverse thread carriers. 50 These comprise a series of links 98, preferably of the sprocket type, each link having projecting therefrom a thread-carrying plate 99 on which one or more thread-engaging fingers 100 may be mounted. These thread- 55 engaging fingers may be in the form of spring

clips having their advancing end portions turned upward, substantially as indicated in Fig. 11, the construction being such that when the grippers place the thread in the path of the advancing ends of the clips, the latter will engage the threads just as they are cut and released from the jaws of the grippers.

As hereinbefore noted, the present instance of the invention proposes to deliver 75 the transverse threads successively as the carriers move forward so that such threads will be placed in succession upon the sticky surface of the fabric as it passes about the roll 24. In order to insure this action, the 80 roll 24, as indicated in Fig. 11, is sufficient in diameter to carry the sticky surfaces of the web 25 into a somewhat higher position than are the transverse threads as they are taken by the carrier toward the roll 24, with the 85 result that the roll 24 will ordinarily act automatically to draw the threads from the fingers 100 of the thread carriers, such action 90 obviously insuring that the transverse threads will be well pressed down into the exposed sticky surface of the web before they are released from the thread fingers 100.

It may be desirable at times to insure the free release of the transverse threads from 95 the thread-carrying fingers in addition to the action of the roll 24, and to this end the present invention contemplates providing a pin 101 below each of the thread fingers 100 and projecting downward as indicated in Fig. 11 to engage the cam surface 102 of a finger opener which may comprise a stationary device substantially as indicated in Figs. 11 and 12, and wherein a cam surface 102 is provided to gradually 100 lift the pins and consequently raise the thread fingers as the carrier moves in its straight path. In the present form of the invention the cam surface is carried by a bracket 103 secured at 104, Fig. 12, to a part 110 of the machine frame, or other suitable support. It may also be desirable that the end portions of the transverse threads shall be depressed after said transverse threads are delivered to the gummed surface of the fabric to insure that the end portions of the transverse threads, as well as the body portions thereof, shall be brought into adhesive 115 relation with the gummed surface of the fabric. To this end the bracket 103 has a portion 105 which projects inward of the thread-carrying plate 99 and extends downward, as indicated in Fig. 12, the construction being such that when the thread fingers 100 carry the threads into engagement with the gummed surface of the fabric, the portions 105 of the bracket 103 will 120 act to depress the ends of the transverse threads.

It is desirable that the transverse thread 125

carriers or chains be held from any sagging movement in order that they may operate with accuracy, and to this end the thread carrying plate 99 is provided with shoulders 5 106, Fig. 8, to rest upon suitable guides 107 projecting from a stationary part 108 secured to the machine frame. Likewise, as indicated in Fig. 8, the thread carriers have downwardly-projecting flanged portions 109, 10 Figs. 8 and 11, which ride upon the stationary bracket 94, and between it and the lower portion of the shoulder 107, the construction being such that the thread carriers are accurately guided in their movement in 15 transferring the threads from the oscillating arms to the gummed surface of the fabric.

It may be desirable at times to adjust the oscillatory arms 40 to vary the path of movement, and as a means to this end, the clamping bolts 38 for securing the sleeves 36 to the shafts 35, may be duplicated on opposite sides of the sleeves as indicated in Fig. 5, so that by proper manipulation the rotary position of the sleeves on the shafts 35 may be 25 changed, as desired. By having the oscillatory arms 40 connected to the shafts 35 by catches, any one of these arms may be temporarily disconnected from the shaft and swung outward for repair or adjustment 30 without disturbing the other arms of the series. It will be noted also, that the transverse threads may, if desired, be made to extend beyond the edges of the fabric or be placed close to the edges as desired, and 35 while the term thread is herein employed to designate the transverse reinforcing elements, it is to be understood that such term is of general character and not necessarily restricted to textile or fibrous elements, as 40 it is obvious that other character of reinforcing elements might be employed.

As will be evident from Fig. 2, the roll 24 about which the fabric 25 passes is located between the two transverse thread carriers 45 or chains, so that by having the upper surface of the roll slightly higher than the rectilinearly moving carriers, the roll itself may act to detach the transverse threads from the carrier as the threads are delivered 50 thereto, but in some cases it may be desirable to further insure this action by releasing the transverse threads from the holding fingers on the carriers, as hereinbefore described. In the described invention it will be seen 55 that the transverse threads are actually laid on the longitudinal threads passing about the roll 24, and that other longitudinal threads alternately arranged with relation to the first-named longitudinal threads, over- 60 lie the transverse threads, so that the transverse and longitudinal threads form of themselves, independent of the paper which they are intended to eventually reinforce, a thread structure wherein the longitudinal and 65 transverse threads are stuck together in per-

manent relation by an adhesive which may be supplied to the threads by the gummed surface of the paper during the formation of the completed reinforced fabric, or the paper fabric might be omitted in which case 70 the longitudinal threads themselves would be passed in contact with the adhesive, substantially as is the paper fabric 25, so that they and the transverse threads would be stuck together in the machine and form an 75 open mesh fabric which could be subsequently applied to the paper, as will be readily understood. The term "material", therefore, is used herein to designate either a fabric or series of longitudinal threads. 80

From the construction described, it will be noted that the present invention draws from a source of supply by gripper means, a series of transverse threads; carries such threads in a transverse direction; places 85 them into position for engagement by thread carriers movable in rectilinear paths; cuts and releases the transverse threads; delivers to the gummed surface of the fabric a series of longitudinal threads, alternate threads of 90 the longitudinal series being preferably above and others below the transverse threads; and then forces two fabrics into superposed relation, whereby the gummed surface or surfaces of the fabrics causes them 95 to adhere and maintain the longitudinal and transverse threads in position, substantially as indicated in the fabric of Fig. 13. Obviously, the particulars of jaw construction, and other details of the mechanism hereinbefore described may be modified and 100 changed within the true scope of the actual invention as pointed out by the claims. It will also be obvious that some features of the invention may be employed independently of the others and that instead of placing the reinforcing threads between two plies of fabric they may be placed on the 105 surface of one ply or web.

What is claimed is:—

1. In a machine of the character described, the combination of means for feeding material to be reinforced, means movable transversely of the machine for simultaneously carrying a plurality of independent reinforcing filaments into parallel relation transversely of the material to be reinforced, and means for releasing the reinforcing filaments from connection with said movable carrying means. 110

2. In a machine of the character described, the combination of means for feeding material to be reinforced, means movable transversely of the machine for simultaneously carrying a plurality of independent reinforcing filaments into parallel relation transversely relatively to the material to be reinforced, means for relatively moving the material to be reinforced and the reinforcing filaments in a direction of approach for ap- 115 120 125 130

plying the reinforcing filaments to the material, and means for releasing the reinforcing filaments from connection with said movable carrying means.

3. In a machine of the character described, the combination of means for feeding and guiding material to be reinforced, a source of supply of reinforcing filaments at one side of the machine, means movable transversely of the machine for taking simultaneously a plurality of filaments from the supply side of the machine and placing them in parallel relation transversely thereof, and means for disconnecting the filaments from the source of supply and from the said movable means.

4. In a machine of the character described, the combination of feeding devices for longitudinally feeding a web of material to be reinforced, a source of transverse thread supply, means for carrying a plurality of threads from said supply transversely of the web to be reinforced and placing them in a plane for delivery to the surface of the web, and means for relatively moving the web and transverse threads toward each other to place the transverse threads upon the surface of the web.

5. A machine of the character described, comprising transverse thread carriers, means for moving the carriers in rectilinear paths, a guide roll located between said carriers for guiding the web to be reinforced into transverse thread receiving position between the rectilinearly moving carriers, and means for delivering transverse threads to said carriers.

6. In a machine of the character described, the combination of a support over which a fabric having an adhesive surface is passed, transverse thread carrying means movable in a rectilinear path for delivering transverse threads to the adhesive surface of said fabric, means for drawing transverse threads from a source of supply and delivering them in predetermined length to said transverse thread carrying means for subsequent delivery to the adhesive surface of said fabric.

- 50 7. In a machine for making fabrics, the combination of a guide about which a series of longitudinal threads are passed, transverse thread carriers, means for delivering transverse threads to said carriers for delivery upon said longitudinal threads, means for thereafter applying other longitudinal threads above the transverse threads that the latter may overlie and underlie alternate longitudinal threads.

- 60 8. In a machine of the character described, the combination of means for longitudinally feeding a web of material to be reinforced, a source of transverse thread supply, gripping means for taking a plurality of threads from said source of supply

and placing them in a plane transversely of the web of material to be reinforced, and means for relatively moving said transverse threads and web of material bodily toward each other for placing said transverse threads in position to be laid upon said web of material.

9. In a machine of the character described, the combination of guiding means for guiding a sheet of material on which transverse threads are to be placed, a source of transverse thread supply, gripping means for carrying a plurality of threads from said source of supply and placing them simultaneously in a single plane transversely with relation to but at one side of the plane of said sheet of material, mechanism for thereafter relatively moving said transverse threads and sheet of material in a direction of approach for direct delivery of said plurality of threads to said sheet of material, and means for releasing said threads from said gripping means.

10. In a machine of the character described, the combination of thread carriers for carrying threads extending transversely between them, means for moving said carriers in rectilinear paths, means for delivering a series of threads to said thread carriers transversely thereof, and means for guiding material between said carriers to receive the transverse threads therefrom.

11. In a machine of the character described, the combination of transverse thread carriers, means for continuously moving said carriers in rectilinear paths, means for delivering a series of transverse threads to said transverse thread carriers, means for guiding material having an adhesive surface between said carriers to receive the transverse threads therefrom, and means for superposing a fabric upon the transverse threads after they have been stuck to the adhesive surface of the first-named fabric.

12. In a machine of the character described, the combination of means for guiding material to be reinforced, means movable transversely of the machine for simultaneously extending a plurality of independent reinforcing filaments in parallel relation transversely relative to the material to be reinforced, a receiver for receiving the plurality of independent reinforcing filaments from the extending means, and means for freeing the independent reinforcing means from connection with the extending means after each extending movement thereof.

13. In a machine of the character described, the combination of means for presenting material to be reinforced, means movable transversely of the machine for simultaneously extending a plurality of independent reinforcing filaments in parallel relation transversely of the material to be

- reinforced and thereafter applying such plurality of reinforcing filaments to the said material, and means for forming said reinforcing filaments in predetermined lengths 5 disconnected from the extending means.
14. In a machine for making reinforced paper fabrics, the combination of transverse thread carriers having thread engaging means, oscillatory arms arranged above said carriers, means for oscillating said arms to draw threads from a source of supply, and deliver them transversely of said carriers, means for cutting the threads, means for lowering said arms to carry the transverse 10 threads into position to be engaged by said thread engaging means, and a guiding device between said carriers and about which a paper fabric is passed, said guide device being arranged to lift the transverse threads 15 from the carriers as the threads are delivered to said fabric. 70
15. In a machine for making reinforced paper fabrics, the combination of movable transverse thread carriers, a guide for directing a paper fabric, gripping means for drawing a plurality of threads from a source of supply and carrying the same transversely of said thread carriers, mechanism for moving said gripping means to 20 ward the thread carriers to deliver the threads thereto, and means for cutting and freeing the threads from said arms to permit said threads to be transported by the thread carriers to the surface of the paper 25 between the carriers. 80
16. In a machine for making reinforced paper fabrics, the combination of a roll about which a paper fabric having an adhesive surface is adapted to pass, transverse 30 thread carriers movable in rectilinear paths and having thread engaging members, and means for delivering a series of transverse threads of a length substantially the same as the width of the fabric to be reinforced to 35 said members to be by them subsequently delivered to the adhesive surface of said paper fabric, and means for freeing the transverse threads from said members. 85
17. In a machine for making reinforced 40 fabrics, the combination of arms at opposite sides of the median line of the machine, transverse thread engaging jaws carried by each of said arms, means for swinging said arms to cause the jaws at one side of the 45 machine to draw threads from a source of supply and deliver the ends to the jaws on the arm at the opposite side of the machine, transverse thread carriers, means for lowering the threads while held by the jaws 50 into position to be engaged by said carriers, thread cutting means, and means for freeing the thread from the jaws at the side of the machine opposite the thread supply. 90
18. In a machine of the character described, a source of transverse thread sup- 55
- ply, a series of grippers for carrying a series of transverse threads from the source of supply transversely of the machine, means for moving said series of grippers transversely of the machine, means for raising and lowering the grippers, and means for freeing lengths of threads from the grippers when they are in lowered position. 95
19. In a machine for reinforcing fabrics, the combination of a transverse thread carrier movable in a rectilinear path, grippers for drawing thread from a source of supply and carrying the same transversely of said carrier, and means for relatively moving said grippers and carrier in a direction of approach to position the transverse thread for engagement by the carrier, and means for freeing a transverse length of thread from the source of supply and said grippers that it may be moved by said carrier. 100
20. In a machine for making reinforced paper fabrics, the combination of grippers mounted at opposite sides of the median line of the machine for drawing thread from a source of supply in a direction transversely of the machine, said grippers having jaws, means for severing the thread at one side of the machine while maintaining the jaws at that side closed upon the thread, and means for freeing the thread from the jaws at the opposite side of the machine. 105
21. In a machine of the character described, the combination of a series of swinging arms for drawing threads from a source of supply in a direction transversely of the machine, a shaft on which said series of arms are independently mounted, means for rocking said shaft, and means for operatively connecting and disconnecting the shaft and said arms. 110
22. In a machine of the character described, the combination of a series of arms for drawing threads from a source of supply transversely of the machine, a shaft on which said arms are mounted, means for rocking said shaft to swing said arms, and a catch for connecting each arm independently to the shaft to permit any arm to be swung independently of the others. 115
23. In a machine of the character described, the combination of a series of arms for drawing threads from a source of supply transversely of the machine, a shaft on which said arms are mounted, means for rocking said shaft to swing said arms, means for raising and lowering said shaft to raise and lower the said arms. 120
24. In a machine of the character described, the combination of feeding devices for feeding a web longitudinally, a source of transverse thread supply, gripping means at each side of the machine, operating mechanism for moving the gripping means toward and away from each other to carry a 125

plurality of threads transversely of the web to be reinforced, and means for relatively moving the transverse threads and web toward each other that the transverse threads may be placed upon the surface of the web.

5 25. In a paper reinforcing machine, the combination of a roll over which a paper fabric having an adhesive surface and a series of longitudinal threads are passed, grippers for drawing a series of transverse threads from a source of supply, transverse thread carriers mounted for rectilinear movement below said grippers to receive the transverse threads and deliver them upon the adhesive surface of the paper fabric above the longitudinal threads, a second roll about which a paper fabric and another series of longitudinal threads pass to be superimposed upon the first fabric with the longitudinal threads overlying the transverse threads, and means for pressing the fabrics and threads together.

10 26. In a paper reinforcing machine, gripping means for drawing threads from a source of supply and carrying them transversely of the machine, a transverse thread carrier comprising rectilinearly movable elements adjacent each side of the machine for receiving the transverse threads from said gripping means, and a paper guide located between the said rectilinearly movable elements and over which a web of paper is passed having an adhesive surface to receive the transverse threads from said carrier.

15 27. In a paper reinforcing machine, grippers for drawing threads from a source of supply transversely of the machine, a transverse thread carrier for taking the threads from the grippers, cutting mechanism for cutting the threads when drawn from said source of supply, and means for periodically raising the cutting mechanism into operative position.

20 28. In a machine for making reinforced paper fabrics, the combination of means for drawing threads from a source of supply in a direction transversely of the machine, means for severing the threads from the source of supply, a guide about which a paper fabric having an adhesive surface is passed, a carrier for taking the transverse threads from said means and delivering them to the adhesive surface of said paper fabric, and means for freeing the ends of the transverse threads when said threads are delivered to the said fabric.

25 29. In a machine for making reinforced paper fabrics, the combination of means for drawing threads from a source of supply in a direction transversely of the machine, a guide about which a paper fabric having an adhesive surface is passed, a carrier for taking the transverse threads from said means and delivering them to the adhesive

surface of said paper fabric, said carrier comprising a chain at each side of the machine having thread engaging fingers.

30 30. In a machine of the character described, the combination of means for guiding and continuously feeding in a longitudinal direction material to be reinforced by independent transverse reinforcing filaments, means for simultaneously drawing a plurality of independent reinforcing filaments from a source of supply and extending the independent filaments in predetermined lengths in parallel relation transversely of the material to be reinforced and applying the independent reinforcing filaments to said material as it is continuously fed.

35 31. In a machine of the character described, the combination of means for guiding material to be reinforced, transverse thread drawing means for simultaneously drawing a plurality of independent threads from a source of supply and placing them in parallel relation transversely of the material to be reinforced, means for disconnecting the threads from the source of supply and drawing means, and means for relatively moving the reinforcing threads and material to be reinforced in a direction of approach.

40 32. In a machine of the character described, the combination of means for presenting material to be reinforced, transverse thread drawing and delivering means for drawing transverse threads from a source of supply transversely of said material, means for severing the threads from the source of supply after each transverse movement of said means, and means for relatively moving the material to be reinforced and the transverse thread drawing and delivering means in a direction of approach.

45 33. In a machine of the character described, the combination of means for continuously moving in a longitudinal direction material to be reinforced, means for intermittently drawing a plurality of independent reinforcing elements simultaneously from a source of supply and placing them in parallel relation transversely to the material to be reinforced, and means for freeing the plurality of independent reinforcing threads from connection with the source of supply and drawing means.

50 34. In a machine of the character described, the combination of means for guiding and feeding a web of material to be reinforced, a series of grippers for periodically carrying a series of threads from a source of supply transversely of the web, a thread carrier at each side of the machine for taking the transverse threads from the grippers, and means for severing the threads from the source of supply that

they may travel with the thread carriers for transfer to the surface of the web.

35. In a machine of the character described, the combination of means for guiding and feeding a web of material to be reinforced, a series of grippers for periodically carrying a series of threads from a source of supply transversely of the web, a rectilinearly moving thread carrier at each side of the machine for taking the transverse threads from the grippers, and means for severing the threads from the source of supply that they may travel with the rectilinearly moving thread carriers for transfer to the surface of the web, and means for freeing the threads from the carriers.

36. In a machine of the character described, the combination of means for guiding and feeding a web of material, a source of transverse thread supply, gripping means at each side of the machine, means for moving the grippers toward and from each other for drawing the threads from the source of supply transversely of the web and causing the grippers at the supply side of the machine to deliver the ends of the transverse threads to the grippers at the other side of the machine, and means for transferring the threads from the grippers to the surface of the web.

37. In a machine of the character described, the combination of means for guiding and feeding a web longitudinally, a source of transverse thread supply, grippers for seizing a series of threads at the supply side of the machine and drawing the threads from said supply, grippers at the opposite side of the machine, and means for moving the grippers at the sides of the machine toward each other to transfer the ends of the threads from the grippers at the supply side of the machine to the grippers at the opposite side and then move the grippers away from each other to place the series of threads transversely of the web.

38. In a machine of the character described, the combination of means for guiding and feeding a web longitudinally, a source of transverse thread supply, grippers for seizing a series of threads at the supply side of the machine and drawing the threads from said supply, grippers at the opposite side of the machine, means for moving the grippers at the sides of the machine toward each other to transfer the ends of the threads from the grippers at the supply side of the machine to the grippers at the opposite side and then move the grippers away from each other to place the series of threads transversely of the web, and means for severing the threads at the supply side of the machine in front of the grippers at that side.

39. In a machine of the character de-

scribed, the combination of means for guiding and feeding a web longitudinally, a source of transverse thread supply, grippers for seizing a series of threads at the supply side of the machine and drawing the threads from said supply, grippers at the opposite side of the machine, means for moving the grippers at the sides of the machine toward each other to transfer the ends of the threads from the grippers at the supply side and then move the grippers away from each other to place the series of threads transversely of the web, and means for transferring the transverse threads from the grippers to the surface of the web.

40. In a machine of the character described, the combination of a longitudinally movable transverse thread receiving element, means for continuously moving said element, a source of transverse thread supply, gripper means for taking a series of threads from the source of supply and extending them in parallel relation transversely of the continuously moving thread receiving element, and means for relatively moving the gripper means and receiving element in a direction of approach to transfer the series of threads to the thread receiving element while it is being continuously moved.

41. In a machine of the character described, the combination of means for feeding material to be reinforced, means for simultaneously drawing a plurality of independent reinforcing filaments from a source of supply and placing them in parallel relation transversely of the material to be reinforced, means for introducing other reinforcing filaments extending longitudinally of the material to be reinforced, and means for releasing the plurality of independent transversely extending reinforcing filaments from connection with the source of supply and drawing means.

42. In a machine of the character described, the combination of means for feeding material to be reinforced, means for simultaneously extending a plurality of independent reinforcing filaments in parallel relation transversely of the material to be reinforced, means for introducing other reinforcing filaments extending longitudinally of the material to be reinforced, some of said longitudinally extending reinforcing filaments being above and others beneath the transversely extending reinforcing filaments.

43. In a machine of the character described, the combination of means for continuously feeding material to be reinforced, means for simultaneously drawing a plurality of independent reinforcing filaments from a source of supply and placing them in parallel relation transversely of the material and applying them to the material to be

reinforced, means for detaching the reinforcing filaments from the drawing means and source of supply, and means for causing the drawing means to again take a plurality of independent reinforcing filaments and simultaneously draw them into parallel relation transversely of the material to be reinforced and deliver said plurality of filaments to the material with the leading filament of the succeeding series in proper spaced relation with the last filament of the preceding series.

44. In a machine of the character described, the combination of means for feeding a paper fabric to be reinforced, a series of grippers movable transversely of the machine for simultaneously drawing a plurality of independent reinforcing filaments from a source of supply at one side of the machine and placing them in substantially parallel relation transversely of said fabric, and means for freeing the reinforcing filaments from the grippers and source of supply for transfer to the surface of the paper to be reinforced.

45. In a machine of the character described, the combination of means for continuously feeding a paper strip to be reinforced, a plurality of grippers for simultaneously drawing a plurality of independent reinforcing filaments from a source of supply at one side of the machine and placing them in substantially parallel relation transversely of said fabric, means for cutting the reinforcing filaments from connection with the source of supply at the supply side of the machine, and means for opening the grippers at the opposite side of the machine to free the reinforcing filaments, and means for moving the reinforcing filaments toward the material to be reinforced when freed from the source of supply and grippers.

46. In a machine of the character described, the combination of means for feeding a paper fabric to be reinforced, a series of grippers movable transversely of the ma-

chine for simultaneously drawing a plurality of independent reinforcing filaments from a source of supply at one side of the machine and placing them in substantially parallel relation transversely of said fabric, means for freeing the reinforcing filaments from the grippers and source of supply for transfer to the surface of the paper to be reinforced, and means for transferring the reinforcing filaments to the surface of the paper after they have been freed from the grippers and source of supply.

47. In a machine of the character described, the combination of means for feeding a web of material to be reinforced, a series of grippers for simultaneously carrying a series of threads in a direction transversely of the material to be reinforced, means for freeing the transverse threads from the source of supply and grippers, a carrier for receiving the threads, and means for actuating the carrier to move the transverse threads in a direction of approach with respect to the material to be reinforced.

48. In a machine of the character described, the combination of means for continuously feeding a web of material to be reinforced, a series of grippers arranged side by side, means for moving the grippers transversely of the machine to simultaneously draw a series of transverse reinforcing filaments from a source of supply at one side of the machine and placing them in substantially parallel relation, means for opening the grippers to free the filaments therefrom, means for cutting the filaments at the supply side of the machine, and a carrier for receiving the filaments and transferring them to the material to be reinforced.

In testimony whereof, I have signed my name to this specification, in the presence of two subscribing witnesses.

CHARLES H. HOWARD.
